UNITED STATES PATENT OFFICE.

MARTIN A. JOHNSON, OF STOUGHTON, WISCONSIN.

AXLE AND SKEIN.

SPECIFICATION forming part of Letters Patent No. 437,398, dated September 30, 1890.

Application filed February 17, 1890. Serial No. 340,711. (No model.)

To all whom it may concern:

Be it known that I, MARTIN A. JOHNSON, a citizen of the United States, residing at Stoughton, in the county of Dane and State of Wisconsin, have invented certain new and useful Improvements in Axles and Skeins; and I do declare the following to be a full, clear, and exact description of the invention, such as will enable others skilled in the art to which it applies to make and use the same, reference being had to the accompanying drawings, and to the letters of reference marked thereon, which form a part of this specification.

My invention relates to vehicles; and its object is to make an axle and axle-skein that shall possess certain advantages in construction and efficiency, as hereinafter set forth, and particularly pointed out in the claims.

In the drawings, Figure 1 is an elevation of one end of my improved axle and skein. Fig. 2 is a vertical longitudinal section of the skein and axle. Fig. 3 is a plan view of a modification, partly in section; and Fig. 4 is a cross-section at the line 4 4, Fig. 1. Fig. 5 is a bottom plan view showing the braces; and Fig. 6 is a cross-section at line 6 6, Fig. 1.

The metallic axle A is preferably composed of steel or iron, and may be of any suitable shape in cross-section, though preferably round throughout. It is screw-threaded from each end back to the point a, where the collar of the skein will come when the latter has been fitted into place. Just back of this point a the axle is bent, as shown in Figs. 1, 2, and 3, giving the proper downward slope or dip to the skein to bring its lower edge horizontal and impart the proper swing to the wheel. I prefer to bend the bar before cutting the threads on it, and the threads should terminate just before the angle in the bar is reached, in order to give the greatest strength possible at that point. It is possible of course to bend the bar after the threads have been cut, or even after the skeins have been screwed on; but I consider it easier and better to give the axle its set before threading it.

The skein B is of cast iron or steel cored out to leave the interior ribs b and chambers b', the latter serving as oil-reservoirs and being provided with filling and outlet ducts b² b³. The latter may run to any desired point along the skein, and may be filled with fibrous

material, if desired, to feed the oil slowly. I prefer to form two chambers, though the number is immaterial. The interior edges of the ribs are cored out to substantially the same cylindrical size, and are then suitably reamed and screw-threaded to fit the threaded end of the axle A. Instead of threading the axle to the point a, I may thread only so much as is shown in elevation in Fig. 2, leaving the remainder of the axle smooth. In this case the outermost rib only need be tapped, the others being reamed to fit the smooth portion of the axle. The threads may be smeared with red lead or the like to prevent the oil from leaking from the chambers.

The end of the axle projects beyond the skein to receive the nut C, which locks the skein in place after it has been screwed upon the axle. To further secure the skein, a key D may be driven into suitable keyways formed in the skein and axle, preferably at the base or collar end of the skein. The end of the key can be clinched against the end of the skein, and may be sunk in a recess prepared for it, as indicated in dotted lines. A key may also be used at the outer end of the skein, if thought necessary.

The exterior of the skein is smooth and tapering, as usual, and has a collar B' at its inner end. Back of the collar extends an ear B², which underlies the horizontal portion of the axle, and partially surrounds it on each side. The groove in the ear in which the axle rests is conical, in order to clear the axle when the skein is being screwed on. Its taper can be calculated beforehand and arranged to fit the bottom of the axle snugly when the skein has been screwed home; but I prefer to run Babbitt metal or some such material E in around the axle, in order to completely fill the space and give the axle a solid bed in the ear. This is especially important when the ear is continued completely around the axle, forming a funnel-shaped extension of the skein, as shown in Fig. 3. In this form, which is somewhat easier to make than the other, a large lune-shaped space will be left around the sides and top of the axle, which should be filled with babbitt to give the axle a more perfect bearing and to afford additional resistance to bending at that point.

In axles that are provided with a wooden

cap-piece F, I groove the under side of it to fit the axle, and shape each end to conform to the ear and collar of the skein. The cap prevents the key D from working loose or coming out.

To permit a smaller axle to be used without any diminution in strength, I may employ a truss-rod G, which is preferably welded at each end to the clip-bar h of the end clip H, 10 this clip-bar h being the flattened end of a brace-rod L, the other end of which is fastened to the hounds K. The under side of the skein-ear B² is notched transversely at b⁴ to receive the clip-bar, and a longitudinal notch b⁵ accommodates the truss-rod, which inclines 15 downward from each end toward the middle of the axle. The clip-bars h' are provided not only with a groove to fit the axle, but with a downwardly-projecting post h², in the 20 end of which is a groove to receive the truss-rod. The clip-bars h³ are formed with wide flat bottoms to afford room for fastening to them the braces L, which underlie the truss-rod G and are attached to the lower edge of 25 the hounds K, as shown in Fig. 5.

Having thus described my invention, what I claim, and desire to secure by Letters Patent, is—

1. The combination, with a metallic axle 30 having a dip or bend near each end and screw-threaded from each end toward the point at which the bend is made, of a cast-metal skein screwed upon the axle and having an ear either surrounding or underlying the unthreaded portion thereof beyond the bend, substantially as described.

2. The combination, with a metallic axle having a dip or bend near each end and screw-threaded from each end toward the point at 40 which the bend is made, of a cast-metal skein screwed upon the axle and having an ear provided with a conical inner surface to underlie and receive the unthreaded portion of the axle beyond the bend, substantially as described.

3. The combination, with a metallic axle 45 having a dip or bend near each end and screw-threaded from each end toward the point at which the bend is made, of a cast-metal skein screwed upon the axle and having an ear

provided with a conical inner surface underlying the unthreaded portion of the axle beyond the bend, and a filling of Babbitt metal or the like occupying the space between the axle and the ear to form a solid bed for the 55 axle, substantially as described.

4. The combination, with the metallic axle A, screw-threaded at each end, of the cast-metal skein B, having the interiorly-threaded ribs b, the lock-nut C on the outer end of the 60 axle, and the key D at the collar end of the axle, substantially as described.

5. The combination, with the metallic axle A, of the skeins B, the wooden cap-piece F, fitting the ends of the skeins, the clips H, the 65 clip-bars h', having the grooved posts h², and the truss-rod G, lying in the grooves, substantially as described.

6. The combination, with the metallic axle A, of the skeins B, having the notches b⁴ in 70 their ears B², the wooden cap-piece F, fitting the ends of the skeins, the clips H, the clip-bars h, lying in the notches b⁴, the grooved clip-bars h' h³, and the truss-rod G, welded to the clip-bars h at its ends and received in 75 the grooved clip-bars, substantially as described.

7. The combination, with the metallic axle A, having a dip or bend and screw-threaded at each end, of the skeins B, having two or 80 more internal screw-threaded ribs to engage the threads on the axle and forming an oil chamber or chambers, inlet and outlet ducts for the oil, said skeins each having a collar and an ear behind the collar having a groove 85 diverging from the axis of the skein, a Babbitt-metal filling in the groove between the ear and the axle, a key D, a lock-nut C, a wooden cap-piece F, clips H, a combined brace and clip-bar h, grooved clip-bars h' h³, and a truss-rod G, welded to the clip-bars h and passing under the grooved clip-bars h' h³, substantially as described.

In testimony whereof I affix my signature in presence of two witnesses.

MARTIN A. JOHNSON.
